(57) **CLAIM**

I claim the ornamental design of a coffee cup recycling container, as shown and described.

DESCRIPTION

FIG. 1 is a perspective view of a variant embodiment of the coffee cup recycling container design of the invention.

FIG. 2 is a front view of the coffee cup recycling container design of FIG. 1.

FIG. 3 is a rear view of the coffee cup recycling container design of FIG. 1.

FIG. 4 is a side view of the coffee cup recycling container design of FIG. 1.

FIG. 5 is an opposite side view of the coffee cup recycling container design of FIG. 1.

FIG. 6 is a top view of the coffee cup recycling container design of FIG. 1; and,

FIG. 7 is a bottom view of the coffee cup recycling container design of FIG. 1.
